(57) **CLAIM**

The ornamental design for a water spray bag toy for children, as shown and described.

DESCRIPTION

FIG. 1 is a perspective view of a water spray bag toy for children showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, showing the water spray bag toy for children in a state of use, with water spouting from the hole.

The broken lines shown in the FIG. 8 are for the purpose of illustrating portions of the water spray bag toy for children, which form no part of the claimed design.
